Sherman C. Heth, Racine, Warren H. Price, Sheboygan, and Charles A. Wuerker, Racine, Wis., assignors to Jacobsen Manufacturing Company, Racine, Wis., a corporation of Wisconsin

Filed Apr. 22, 1966, Ser. No. 1,986

Term of patent 14 years

(Cl. D40—1)

FIG. 1 is a top plan view of a lawn mower hand grip showing our new design;

FIG. 2 is a front elevational view thereof;

FIG. 3 is a rear elevational view thereof;

FIG. 4 is an elevational view taken from the right side thereof;

FIG. 5 is an elevational view taken from the left side thereof; and

FIG. 6 is a cross sectional view taken on line 6—6 of FIG. 2.

The fragmentary broken line representation of a lawn mower handle in FIG. 1 is for purposes of illustration only.

We claim:

The ornamental design for a lawn mower hand grip, substantially as shown and described.
